[57] ABSTRACT

[21] Appl. No.: 469,879

An improved construction for an electrical loudspeaker includes a housing enclosing a diaphragm and a magnetic motor structure secured to the housing. An aperture in the housing has a flange extending into a coaxial opening in the motor structure and crimped thereto, joining the housing to the motor structure and creating an air gap which has no machined surfaces or edges. An electro-magnetic voice coil secured to the diaphragm extends through the aperture in the housing and into the air gap, through which passes the magnetic field of the motor structure. Because the air gap has no machined surfaces or edges, it is free of chips and other foreign materials which are the major cause of speaker malfunction and failure. Furthermore, this method of construction is efficient and accurate and may be easily accomplished by automated methods.

FIG_1

FIG_2

ELECTRODYNAMIC LOUDSPEAKER WITH BASKET MOUNTING TO POLE PIECE

BACKGROUND OF THE INVENTION

In the manufacture of permanent magnet, moving coil type loudspeakers the magnetic structure which forms an air gap for the moving coil is fixedly mounted to the housing which supports the diaphragm and moving coil. Generally the air gap is formed by a cylindrical magnet or core piece extending into a larger diameter opening in a plate. The opening in the plate is formed by drilling, punching, or similar methods which create metal dust and chips. The plate is then secured to the housing by welding, spot welding, staking, drilled and tapped holes or other methods which may create more metal dust and particles. Because the particles cannot be completely removed, the subsequent magnetization of the motor structure draws the remaining particles into the air gap. The particles interfere with the clearance between the moving coil and the sides of the air gap, rubbing and causing severe distortion of reproduced sound, or blocking the moving coil altogether.

Another common failure of prior art loudspeakers is the misalignment of the magnet structure with the housing during assembly of the two parts. A slight misalignment during this assembly causes the air gap to be nonconcentric about the moving coil, causing rubbing and the resultant sound distortion.

Both the problems of chip and dust in the gap, and the misalignment of the magnetic structure have proved to be serious in the prior art, causing an unwarranted and costly high proportion of rejected loudspeakers during manufacture.

SUMMARY OF THE INVENTION

The present invention is directed toward an improved construction of an electrical loudspeaker which overcomes the enumerated deficiencies of prior art devices. It comprises a speaker diaphragm which is enclosed in a housing, and an electromagnetic voice coil coaxially joined to the diaphragm and extending through an aperture in the housing. A permanent magnet motor structure with a plate adjoining the housing has an opening therein which coaxially registers with the aperture in the housing. A flange extruded from the edge of the aperture extends through the opening in the plate of the permanent magnet motor structure and is crimped into an annular groove about the opening of the plate, securing the housing and motor structure together and creating a smooth air gap in which the voice coil dwells.

THE DRAWING

FIG. 1 is a partially cutaway side elevation of the present invention; and

FIG. 2 is an enlarged, exploded view of a portion of the present invention.

DESCRIPTION OF THE PREFERRED EMBODIMENTS

As shown in FIG. 1, the present invention includes a housing or basket 5, generally formed conically and symmetrically about axis A—A. The housing includes a transverse annular portion 6, to which a conical diaphragm 7 is secured with adhesive. To the narrow end of the diaphragm a cylindrical coil form 8 is secured. Wound about the coil form is an electromagnetic voice

coil 9, which provides the vibratory power for the diaphragm. A dust cap 11 seals the narrow end of the diaphragm and prevents any foreign material from entering and obstructing the voice coil. A flexible dia-

phragm or spider 12, secured about the narrow end of the diaphragm, similarly isolates the voice coil from contamination by airborne particles. The permanent magnet structure 13 includes a plate 14 of rectangular or circular configuration with a circular aperture 15 therethrough; the axis of the aperture coincident with axis A—A. The edges of aperture 15 are coined annular surfaces 17 and 20 as shown also in FIG. 2. A U-shaped bracket 18 is joined to the plate 14 by welding, adhesives or the like. Secured between the bracket 18 and the plate 14 is a cylindrical permanent magnet 19, to which a stepped cylindrical core piece 21 is joined. The magnet and core piece are axially coincident with the axis A—A, and the smaller magnet is also polarized along this axis. Alternatively, a magnet of smaller radius may be employed, extending from the bracket 18 into the portion of the aperture occupied by the tip 21 shown.

With the core piece 21 extending into the aperture 15, a magnetic circuit to conduct the flux lines of the magnet is formed, comprising the magnet 19, the bracket 18, the plate 14, the air gap 22, the core piece 21 and again the magnet. Extending into the air gap is the voice coil 9, which is thus intersected by the flux lines of the magnet 19. An alternating current applied to the voice coil creates an alternating magnetic field which acts against the field of magnet 19, creating the varying force which causes the diaphragm 7 to vibrate.

The magnet structure 13 is secured to the housing 5 by means of a flange 23, which extends from the circular opening 24 in the narrow end of the housing 5, as shown in FIG. 2. A raised annular surface 25 is formed at the base of the flange. In assembling the housing and magnet structure, the plate is joined to the housing with the flange extending into and through the aperture 15 and with the raised annular surface 25 fitting into the adjacent coined annular surface 17. The portion of the flange extending through the aperture is then crimped radially outward and onto the coined surface 20, securing the plate and its related magnet structure to the housing.

It should be noted that the members thus joined are centered with respect to each other. Because the outside diameter of the flange is just small enough to pass through the aperture 15 in the plate, the possibility of misaligning the housing and plate is eliminated. Furthermore, the process of joining the housing and magnet structure furnishes the air gap with an outer wall formed by the smooth surface of the flange. The machined edges of the aperture 15, which can contribute the minute metal shavings which rub against the moving voice coil and distort the reproduced sound are denied access to the air gap by the clean surface of the flange. Thus this method of speaker assembly also eliminates the major cause of loudspeaker malfunction that is encountered during manufacture.

Although the present invention has been described with respect to a particular form of housing and magnet structure, it should be appreciated that the present invention may be employed in other forms of loudspeakers. For example: the same speaker construction may be used with disc ceramic permanent magnets commonly known in the art, or with electromagnets.

We claim:

1. An electrical loudspeaker comprising:
 a housing having a circular opening therein,
 diaphragm means secured within said housing for
 generating sound waves,
 5 magnetic means for creating a constant magnetic
 field, said magnetic means including an aperture
 therein,
 electromagnetic means secured to said diaphragm
 means, for vibrating said diaphragm means,
 flange means, formed integrally with said housing
 10 about said circular opening in said housing and
 extending through said aperture in said magnetic
 means, and
 flange receiving means within said magnetic means
 15 for retaining said flange means, said magnetic
 means including a plate in which said aperture is

formed and an annular recess concentric about
 said aperture on one side of said plate,
 said housing including an annular shoulder concentric
 about said circular opening and adapted to be
 received in said annular recess to center said hous-
 ing with respect to said plate

said flange receiving means including an annular
 groove concentric about said aperture on the other
 side of said plate, said flange means being crimped
 into said annular groove and retained thereby.

2. The electrical loudspeaker of claim 1, wherein said
 flange means comprises an annular flange about said
 circular opening and within said annular shoulder, and
 said electromagnetic means comprises a hollow, cylind-
 ical electromagnetic coil concentrically and freely
 received within said annular flange.
